RECEPTACLE AND SUPPORT THEREFOR

William E. House, Toledo, Ohio, assignor to
Owens-Illinois Glass Company, a corporation
of Ohio

Application July 29, 1939, Serial No. 287,386

5 Claims. (Cl. 47—11)

My invention relates to improvements in receptacles and supports therefor and more particularly is concerned with the provision of a novel form of receptacle and support for use in the gathering of turpentine gum.

An object of my invention is the provision of a novel form of receptacle preferably made of glass and a support therefor formed of relatively heavy gage wire, the latter being of such structure that it requires only a comparatively short length of wire in its formation.

A further object of the invention is the provision of supporting means for a receptacle of the above character which may well be utilized as a bail or handle for transporting the receptacle from place to place.

Other objects will be in part apparent and in part pointed out hereinafter.

In the accompanying drawing:

Fig. 1 is a side elevational view showing the receptacle and support embodying my invention attached to the trunk of a tree.

Fig. 2 is a detail side elevational view of the receptacle and support.

Fig. 3 is an elevational view taken at right angles to Fig. 2.

Fig. 4 is a perspective view of the support.

Fig. 5 is a fragmentary perspective view showing another form of loop that may be employed.

In the illustrated embodiment of my invention it is shown supported upon the trunk 6 of a tree from which turpentine gum or sap flows down a trough 7 to the receptacle 8 or container, the latter being removably secured to the tree by a support 9, a looped portion of which engages a nail 10 or like fastener, which has been driven into the trunk 6.

The receptacle 8 includes a bottom 11, an upwardly and outwardly sloping continuous side wall 12 and a radially outwardly directed bead 13 or rib at its upper margin. This rib provides a substantially continuous downwardly facing shoulder 14 or ledge adapted for engagement with a portion of the support 9 as will be apparent presently. Opposed radial recesses 15 are formed at diametrical points in the rib 13, externally of the receptacle, for engagement with portions of the support 9.

The support as shown, is formed from a length 50 of relatively heavy gage wire and is substantially semi-circular in shape and designed for engagement substantially throughout its length with the aforementioned shoulder 14. The support may be said to include a pair of curved arms 55 16 which are connected at adjacent ends by an

upstanding substantially U-shape loop 17, which loop is intended for engagement with the aforementioned nail 10 or other fastening device. The other, or outer, ends of the arms 16 are bent upwardly as at 18 and thence inwardly to form pintles 19, or fingers, which project into the pair of diametrically opposed recesses 15. The dimensions of the support and rib 13 are such that the arms 16 firmly engage with the downwardly facing shoulder 14 and offer substantial support 10 for the receptacle. If desired, the support may be removed from the position shown in the drawing and then attached to the receptacle in the same fashion as and for the same purpose as, the bail or handle ordinarily employed in transporting a water bucket or like receptacle.

In Fig. 5 I have illustrated another form of loop 17 in which the wire is twisted as at 20. Obviously, various types of loops may well be employed in this connection.

Modifications may be resorted to within the spirit and scope of the appended claims.

I claim:

1. In combination, a bucket-like receptacle having an open upper end, an outstanding rib at said upper end forming a downwardly facing shoulder about the periphery of the receptacle, said rib having a pair of diametrically opposed radial recesses in its outer face, and a support for the receptacle including a semi-circular element positioned in engagement with said shoulder and fingers at the ends of said element projecting into the recesses. 25

2. In combination, a bucket-like receptacle having an open upper end, an outstanding rib at said upper end forming a downwardly facing shoulder about the periphery of the receptacle, said rib having a pair of diametrically opposed radial recesses in its outer face, a support for the receptacle including a semi-circular element positioned in engagement with said shoulder and fingers at the ends of said element projecting into the recesses, and a loop-like offset between the ends of said element. 35

3. In combination, a bucket-like receptacle having an open upper end, an outstanding rib at said upper end forming a downwardly facing shoulder about the periphery of the receptacle, said rib having a pair of diametrically opposed radial recesses in its outer face, and a support for the receptacle including a semi-circular element positioned in engagement with said shoulder, said element having its end portions inclined upwardly and thence inwardly for reception in said recesses. 45

4. In combination, a bucket-like receptacle having an open upper end, an outstanding rib at said upper end forming a downwardly facing shoulder about the periphery of the receptacle,
5 said rib having a pair of diametrically opposed radial recesses in its outer face, a support for the receptacle including a semi-circular element positioned in engagement with said shoulder, said element having its end portions inclined
10 upwardly and thence inwardly for reception in said recesses, and a loop-like offset between the ends of said element.
5. In combination, a bucket-like receptacle

having an open upper end, an outstanding rib at said upper end forming a downwardly facing shoulder about the periphery of the receptacle, said rib having a pair of diametrically opposed radial recesses in its outer face, a support for the receptacle including a semi-circular wire positioned in engagement with said shoulder and having its ends bent upwardly and radially inward into the recesses and a substantially inverted U-shaped offset between the ends of said wire. 5
